US0D1099988S

(12) **United States Design Patent** (10) Patent No.: **US D1,099,988 S**
(45) Date of Patent: ** Oct. 28, 2025

(54) **SCREED ALIGNMENT TOOL FOR WORK MACHINE**

(71) Applicant: **Caterpillar Inc.**, Peoria, IL (US)

(72) Inventors: **Steven Goutermont**, Saint Michael, MN (US); **Austin James Hidy**, Crystal, MN (US)

(73) Assignee: **Caterpillar Inc.**, Peoria, IL (US)

(***) Term: **15 Years**

(21) Appl. No.: **29/937,150**

(22) Filed: **Apr. 12, 2024**

(51) LOC (15) Cl. **15-03**

(57) **CLAIM**

The ornamental design for a screed alignment tool for work machine as shown and described.

DESCRIPTION

FIG. 1 is a perspective view of a screed alignment tool for work machine showing our new design;
FIG. 2 is another perspective view thereof;
FIG. 3 is a front view thereof;
FIG. 4 is a rear view thereof;
FIG. 5 is a left side view thereof;
FIG. 6 is a right side view thereof;
FIG. 7 is a top view thereof; and,
FIG. 8 is a bottom view thereof.
